UNITED STATES PATENT OFFICE

GUY S. PETERSON, OF EAST CLEVELAND, OHIO, ASSIGNEE TO THE STRONG, CARLISLE AND HAMMOND COMPANY, OF CLEVELAND, OHIO, A CORPORATION OF OHIO

RESISTANCE FURNACE

Application filed April 15, 1930. Serial No. 444,429.

My invention relates to electric furnaces of resistance type which are intended for use in heat treating processes wherein the work must be quickly raised to a high temperature, but without melting any part before it is all heated through. To this end certain of the resistance elements must be capable of quickly generating great heat, and therefore one of the aims of my invention is to so arrange the furnace elements that the work will not be directly exposed to surges of heat from the resistors. Another aim is the provision of circuits, controls, and a mode of operation such that the requisite temperatures are very rapidly attainable.

One sort of work for which my furnace is intended is the heat-treating of sharp-edged high-speed steel tools at temperature ranges just below the melting point of the steel, with time limitations measured in seconds. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a transverse cross section on the line 1—1 of Fig. 2; Fig. 2 is a longitudinal cross section on the line 2—2 of Fig. 1; and Figs. 3 and 4 are diagrams of possible circuits.

Referring particularly to Fig. 1, my furnace is of commercial type in its general form, comprising a heating chamber 1, lined with refractory material 2, which is again surrounded by the usual insulation 3, externally cased as at 4, the whole assembly being supported, in the smaller sizes, on a suitable stand 5. Access to the heating chamber is had by a passage 6, closed by a door here shown as including an inner refractory tile 7 and an outer insulating section 8, the whole assembly resting on a shelf 9 and movable on guides 10. A peep hole 11 allows the work

to be watched. A suitable rack 12 within the chamber 1 supports a removable work-holding muffle 13, here shown as a tray made of a suitable heat-resisting material, such as carborundum, and having a flat bottom 14 and relatively low sides 15. The muffle 13 is held in place by a removable tile 16.

Resistors 21, 22 and 23 are arranged upon suitable holders 24 within the heating chamber 1, and are connected in their circuits by water-cooled conductors, such as 25. The resistors are here shown as grouped in pairs, the grouping, however, being a matter of convenience. In the type of furnace illustrated, the resistors are of carbon silicide, but other materials capable of carrying high current densities, would be suitable. It will be particularly noted that the resistors are so placed relatively to the muffle 13 that some part of the muffle will always be between the work in the muffle and each resistor, or in other words, that the bottom and sides 15 of the muffle always act to screen off direct radiation of heat to the work. For this purpose the top of the muffle side 15 is made as high as the top of the upper resistor bar of each side pair 21 and 22, it being understood that the work will be kept below the top of the side 15. The reason for this has been suggested in the statement of invention, and will be further explained below.

An electrical system for the furnace is shown in a transverse diagrammatic view in Fig. 3. The resistors 21 and 22 at the sides of the furnace are connected in series on a single circuit, parts of which are shown in solid lines and part dotted to indicate connections on the front and rear ends, respectively, of the resistors. Current for the circuit is supplied from the line 23 and is cut on and off by suitable thermally responsive instruments. Such instruments may conveniently comprise a thermocouple T appropriately located in the heating chamber and connected to a pyrometer controller P, which in turn actuates a controller panel C between the resistors 21, 22 and the line 23. The resistors 24 under the muffle are on their own separate circuit supplied from another line 25. This circuit includes a cut-off S which will ordinari-

ly be manual only, although it may be thermally governed, but within a different temperature range from the pyrometer setting, as will be apparent from the description of the operation, below.

Another arrangement of the resistor circuits is shown diagrammatically in Fig. 4, wherein the constant circuit includes only the two top resistors 31, and the remaining four, 10 32, 33, are automatically controlled. For the forms shown in Figs. 3 and 4, having all resistors of the same size and connected in series, and using two-wire supply systems, the supply for the four-resistor circuit may conveniently be 220 volts, and that for the two-resistor circuit, 110 volts. The circuit details are, of course, subject to modification according to the characteristics of the resistors, of the current, and so on. A series arrangement of the resistors is illustrated in 20 Figs. 3 and 4, but it will be understood that, although this is a convenient showing, the exact hook-up of the resistors is subject to variation as desired, within the limits of the 25 invention.

In operation, the resistors in the circuit controlled by the switch S (24 in Fig. 3; 31 in Fig. 4) are all kept on constantly and are designed and run so as to keep the heat of the 30 furnace not quite up to the required working temperature. For example, if a working temperature of 2450° F. should be required, the bottom resistors would be relied on to supply the heat to keep the chamber 1 up to 35 about 2400°, and the resistors in circuit with the panel C (21, 22, Fig. 3; 32, 33, Fig. 4) to bring it up quickly to 2450° F., after opening the door and introducing new work had cooled it down somewhat. The temperature 40 of the constantly-operated resistors is, of course, related to the character of the work.

In the treatment of high-speed steel articles, the temperatures are on the order of 2000° F. to 2450° F., the work must be brought 45 up to the maximum temperature within a few seconds, but without allowing the edges to melt before the thicker parts are heated through. Even though the work is preheated before loading it into the furnace, the 50 opening of the door and the introduction of the work will lower the heating chamber temperature, perhaps 50°. The control system T, P, C, will then operate to cut in the additional resistors, which are capable of operating 55 at a high current density, such as 80 watts per square inch of surface, and which therefore give a surge of heat which would melt the edges of the tools before the thicker parts could heat up, except that the work is 60 screened from the direct action of this surge by the muffle walls 12.

While I have shown and described an embodiment of my invention designed for temperature ranges above the reach of metallic 65 resistors, it will be apparent that the prin-

ples could be embodied in other forms, either for higher temperatures, or for lower ranges. For example, the screening principle and the quick supply of the final heat could be used for certain types of ceramic work, at temperatures on the order of 1500° F. to 2000° F.

The principles of the invention are also applicable to furnaces having a deeper muffle, a full muffle, or to pit type furnaces, by proper structural arrangements to apply added heat 70 rapidly while screening the work from the heat surge or direct radiation from the resistors.

It will therefore be understood that I do not limit myself to the form of the invention above described, but that it may be embodied 80 in any manner within the scope and spirit of the appended claims.

What I claim is:

1. In an electrical furnace, an open-topped work-receiving muffle having upstanding sides, a group of resistors therebeneath, a group of resistors therealongside, the sides of the muffle extending at least as high as the top portion of the side resistors.

2. An electric resistance furnace comprising, in combination, an open-topped muffle, a bottom and upstanding sides on said muffle, said bottom and sides defining a work-holding space, a plurality of heating elements in said furnace so disposed that some portion of the muffle is interposed between every heating element and the work-holding space, and means for independently regulating various of the said heating elements.

3. An electric resistance furnace including, in combination, a muffle partly open within said furnace, a plurality of resistors adjacent said muffle, elements of said muffle directly interposed between said resistors and work in said muffle, two electrical circuits in said furnace each including certain of said resistors, and independent control means for each circuit.

4. An electric resistance furnace including, in combination, a muffle partly open within said furnace, a plurality of resistors adjacent said muffle, elements of said muffle directly interposed between said resistors and work in said muffle, two electrical circuits in said furnace each including certain of said resistors, independent control means for each circuit, one of said control means being responsive to narrow thermal changes.

5. In an electrical furnace, an open-topped work-receiving muffle having upstanding sides, a group of resistors therebeneath, a group of resistors therealongside, the sides of the muffle extending at least as high as the top portion of the side resistors, and separate control means for each of said groups.

6. In an electrical furnace, an open-topped work-receiving muffle having upstanding sides, a group of resistors therebeneath, a group of resistors therealongside, the sides

- of the muffle extending at least as high as the top portion of the side resistors, separate control means for each of said groups, the control means for the side groups being thermo-responsive.
7. In an electrical furnace, an open-topped work-receiving muffle having upstanding sides, a group of resistors therebeneath, a group of resistors therealongside, the sides 10 of the muffle extending at least as high as the top portion of the side resistors, an electrical circuit including a thermostat and said side groups of resistors, another electrical circuit including the bottom group of resistors.
8. An electric furnace comprising a work-receiving space, a plurality of resistors thereabout, a circuit including certain of said resistors and means for intermittently switching said certain resistors on or off, screening means between said certain resistors and said work-receiving space.
9. An electric furnace comprising a plurality of resistors, said resistors being divided 25 into groups, one of said groups being adapted for relatively constant and the other for relatively intermittent operation, a container adapted to hold work in said furnace, said container constituting a screen between said intermittently operated resistors and the work.
10. A method of operating a resistance furnace which comprises interposing a screen between the resistors and work in the furnace, and operating said resistors in groups, using one group to give a constant supply of heat slightly below the required temperature, and the other to give intermittent additional heat to the required temperature.
11. A method of operating a resistance furnace which comprises operating said resistors in groups, using one group to give a constant supply of heat slightly below the required temperature, and the other to give intermittent additional heat to the required temperature, and interposing a screen between the intermittently operated resistors and work in the furnace.
12. An electric resistance furnace including, in combination, a muffle within said furnace, a plurality of resistors adjacent said muffle, elements of said muffle directly interposed between said resistors and work in said muffle, a plurality of electrical circuits in said furnace each including certain of said resistors, and pyrometer control means in certain of said circuits.
13. An electric resistance furnace including, in combination, a hearth, a plurality of resistor bars arranged parallel to said hearth, certain of said resistor bars being adapted for constant operation and the others for intermittent operation, and screen means between said intermittently operable resistor
- bars and the work-holding space of said hearth.
14. An electric resistance furnace including, in combination, a hearth, a plurality of resistor bars arranged parallel to said hearth, 70 said resistor bars being arranged in electrical and structural groups, certain of said groups being adapted for intermittent operation, certain other of said groups being adapted for constant operation, and screen 75 means between said intermittently operable groups and the work-holding space in said hearth.
- Signed by me this 11th day of April, 1930.
